UNITED STATES PATENT OFFICE.

CHRISTIAN G. LEHMANN, OF DETROIT, MICHIGAN.

DISPENSING-CABINET.

1,207,942.

Specification of Letters Patent. Patented Dec. 12, 1916.

Application filed June 10, 1916. Serial No. 102,820.

To all whom it may concern:

Be it known that I, CHRISTIAN G. LEHMANN, a citizen of the United States of America, residing at Detroit, in the county of Wayne and State of Michigan, have invented certain new and useful Improvements in Dispensing-Cabinets, of which the following is a specification, reference being had thereto to the accompanying drawings.

10. This invention relates to a dispensing cabinet for foodstuffs, and more particularly to a preserving or refrigerating cabinet adapted for holding and dispensing perishable foodstuffs, as butter, cheese and sliceable matter.

15. The primary object of my invention is to provide a dispensing cabinet that may be advantageously used for slicing bars of butter into blocks or "pats" of a uniform size, 20 and separating the blocks of butter whereby the bar of butter may be intermittently or progressively fed into position to be sliced and the blocks cut therefrom delivered from the cabinet to be easily handled.

25. Another object of my invention is to provide a dispensing cabinet having a removable refrigeratory chamber that permits of easy access being had to the operating mechanism of the cabinet whereby a bar of 30 butter can be correctly placed into position to be sliced.

35. A further object of my invention is to provide a dispensing cabinet wherein the parts are constructed with a view to reducing the cost of manufacture and retain those features by which butter cutting operations may be observed, accurate cutting assured, and a sanitary preserving cabinet secured that may be economically used in 40 large restaurants and the culinary apartments of other institutions.

45. The mechanical construction by which I attain the above and other objects will be hereinafter specifically described and then claimed, and reference will now be had to the drawings, wherein—

Figure 1 is a longitudinal sectional view of the dispensing cabinet; Fig. 2 is a front elevation of the same, partly broken away and partly in section; Fig. 3 is a perspective view of the detached conveyer support; Fig. 4 is a plan of a detached conveyer; Fig. 5 is an enlarged longitudinal sectional view of a portion of the cabinet, illustrating the cutting device.

A cabinet in accordance with this invention comprises a casing having a bottom 1, a rear wall 2, and side walls 3, said side walls projecting beyond the bottom 1 and at the forward edge of said bottom said side walls 60 are connected by a transverse partition 4. The bottom 1, walls 2 and 3, and partition 4, are preferably made of inner and outer spaced metallic shells between which is placed an insulation material 5, as mineral 65 wool or cellular asbestos. The upper edges of the walls 2 and 3 and the partitions 4 are adapted to support a lid 6 and this lid may be constructed similar to the walls and partition. 70

The partition 4, at the bottom 1, has an opening 7 and mounted upon the bottom 1, partly within the opening 7 of the partition 4, is a fixed bearing 8 longitudinally alining with an adjustable bearing 9 on the bottom 1, adjacent the rear wall 2. The bearings 8 and 9 are slotted, as at 10, to receive the pintles 11 and 12 of rolls 13 and 14 respectively. 75

Detachably mounted upon the pintles 11 80 and 12, between the ends of the rolls 13 and 14 and the bearings 8 and 9 thereof, are the slotted side arms 15 of a longitudinally disposed conveyer support 16 and this support is adapted to prevent sagging of the upper side of an endless belt or conveyer 17 trained over the rolls 13 and 14. The belt or conveyer is adapted to hold a bar of butter or other foodstuff, and to preserve the same while in the cabinet, a metallic container 18 is placed therein adapted for holding a refrigeratory agent, as ice. The container 18 has the bottom thereof provided with a housing that straddles or bridges the conveyer 17 and provides clearance for a bar 90 of butter on the conveyer. At the rear end of the container 18 there is a drip tube 20 extending through a sleeve 21 in the bottom 1 of the cabinet, and said cabinet may be supported in an elevated position by legs 95 22, to permit of a pan or other receptacle being placed under the rear end of the cabinet to receive drippings from the container 18. 100

The forward ends of the walls 3 are connected by a transparent plate 23, co-operating with said walls and the partition 4 in providing an operating compartment 24 which has the top thereof closed by a plate 25. 105 110

Secured to the outer side of the partition 4 is a metallic plate 26 having an opening 27 and a slot 28. The plate 26 is provided with guides 29 for plungers 30 and 31, the former being connected to the latter, as at 32, and the latter extending through the plate 25 whereby it may be depressed and both plungers slide in the guides 29. The lower end of the plunger 31, has a head 33 provided with a pawl 34 adapted to engage a ratchet wheel 35 on the pintle 11 of the roll 13 so that said roll and the conveyer 17 will be intermittently moved at each downstroke of the plunger 31. To prevent accidental movement of the conveyer, while the plunger 31 recedes, a resilient dog 36 is mounted upon the bottom 1 of the cabinet to normally engage the ratchet wheel 35.

In providing the plate 26 with the opening 27, said plate is formed with a ledge 37 at the lower edge of the opening 27 and below said ledge is pivotally mounted a tilttable shelf 38 which is held normally in a plane with the ledge 37 by a spring 39. The ledge 37 and the shelf 38 are adapted to receive the forward end of the bar of butter on the conveyer 17, so that the forward end of the bar of butter may be sliced into blocks or "pats" and delivered into the lower end of the operating compartment 24.

To slide the butter bar when on the ledge 37 and the shelf 38, the plungers 30 and 31 are connected by a transverse wire 40, and adjacent said wire is a projection 41 on the plunger 30 adapted to engage the tilttable shelf 38 and tilt the same to discharge a block or "pat" of butter after the same is severed from the butter bar.

To hold the plungers 30 and 31 in an elevated position, the plunger 30 is connected by a coiled retractile spring 42 to the plate 25, and the lower end of the plunger 30 is slightly curved, as at 43, to engage and open a normally closed trap door 44 closing an opening 45 in a plate 46 forming the bottom of the operating compartment 24.

In operation, a depression of the plunger 31 causes the conveyer 17 to advance the bar of butter thereon until the end of the bar protrudes through the opening 27. With the plungers 30 and 31 descending the wire 40 cuts the end of the bar of butter and releases a block or "pat" of butter on the tilttable shelf 38, which is tilted as the plungers 30 and 31 complete the downward stroke. Prior to the shelf 38 being tilted by the projection 41 of the plunger 30, said plunger engages the trap door 44 and opens the same, whereby the severed block or "pat" of butter may drop into a receptacle placed beneath the opening 45. The trap door 44 prevents dust or foreign matter from entering the operating compartment 24 and eventually reaching the bar of butter on the conveyer. The closed trap door also assists in

maintaining a low temperature within the insulated cabinet.

From the foregoing it will be observed that I have devised means for independently moving a bar of butter into position to be sliced and have also devised means for simultaneously slicing the butter and discharging the same from the refrigeratory cabinet. With the conveyer actuated in advance of the slicing operation, the greater part of the butter upon the conveyer is maintained beneath the container 18 and the cooling agent used in connection with this container will maintain the bar of butter solid and firm just as though preserved in an ordinary refrigerator.

It is thought that the operation and utility of the dispensing cabinet will be apparent without further description, and while in the drawing there is illustrated a preferred embodiment of my invention, it is to be understood that the structural elements are susceptible to such variations and modifications as fall within the scope of the appended claims.

What I claim is:—

1. A butter dispensing cabinet comprising a casing having insulated walls, an endless conveyer normally extending into one of the casing walls adapted to feed a bar of butter therethrough, and butter slicing and conveyer actuating means on the wall of said casing and adapted by a single operation for actuating the conveyer in advance of slicing butter.

2. A butter dispensing cabinet comprising a casing having insulated walls, an endless conveyer in said casing extending into one of said casing walls adapted to feed a bar of butter therethrough, butter slicing and conveyer actuating means on the wall of said casing adapted for actuating the conveyer in advance of slicing butter, and a tilttable shelf supported by the same casing and adapted to be tilted by said means after butter is sliced.

3. A butter dispensing cabinet comprising a casing having insulated walls, an endless conveyer extending into one of the casing walls and adapted to feed a bar of butter therethrough, a container over said conveyer adapted to hold a refrigeratory agent, and butter slicing and conveyer actuating means on the wall of said casing adapted for actuating a conveyer in advance of slicing butter.

4. A butter dispensing cabinet comprising a casing having insulated walls, a conveyer in said casing, extending into one of the casing walls and adapted to feed a bar of butter therethrough, a container over said conveyer adapted to hold a refrigeratory agent, butter slicing and conveyer actuating means on the wall of said casing adapted for intermittently actuating said conveyer in advance of slicing butter, and a tilttable shelf sup-

- ported by the same casing wall adapted to receive butter and adapted to be tilted by said butter slicing means.
5. A butter dispensing cabinet comprising a casing, a partition in said casing dividing said casing into an operating compartment and a refrigeratory compartment, a conveyer in the latter compartment of said casing adapted to feed a bar of butter through said partition, and butter slicing means carried by said partition adapted for actuating said conveyer in advance of slicing butter.
6. A butter dispensing cabinet comprising a casing, a partition in said casing dividing said casing into an operating compartment and a refrigeratory compartment, a conveyer in the latter compartment of said casing adapted to feed a bar of butter through said partition, butter slicing means carried by said partition adapted for actuating said conveyer in advance of slicing butter, and a tilttable shelf supported by said partition adapted to be tilted by said slicing means after butter is sliced.
7. A butter dispensing cabinet comprising a casing, a partition in said casing dividing said casing into an operating compartment and a refrigeratory compartment, a lid for the refrigeratory compartment of said casing, a trap door for the bottom of the operating compartment of said casing, a conveyer in the refrigeratory compartment of said casing adapted to feed a bar of butter through said partition, and butter slicing means carried by said partition adapted for actuating said conveyer in advance of slicing butter, and adapted for opening said trap door.
8. A butter dispensing cabinet comprising a casing, a partition in said casing dividing said casing into an operating compartment and a refrigeratory compartment, a lid for the refrigeratory compartment of said casing, a trap door for the bottom of the operating compartment of said casing, an endless conveyer in the refrigeratory compartment of said casing adapted to feed a bar of butter through said partition, butter slicing means carried by said partition adapted for actuating said conveyer in advance of slicing butter, and a tilttable shelf supported by said partition adapted to be tilted by said slicing means.
9. A butter dispensing cabinet comprising a casing, a partition in said casing dividing said casing into an operating compartment and a refrigeratory compartment, a conveyer in the latter compartment of said casing adapted to intermittently feed a bar of butter through said partition, a tilttable shelf supported by said partition, a plunger slidably supported on said partition and adapted for actuating said conveyer, a plunger movable in synchronism with said conveyer actuating plunger and adapted for tilting said shelf, and butter slicing means connecting said plungers.
10. A butter dispensing cabinet comprising a casing, a longitudinally disposed conveyer therein adapted to shift a bar of butter toward one end of said casing, a detachable container in said casing adapted for refrigeratory agents and having a housing providing clearance for said conveyer, and butter slicing and conveyer actuating means in an end of said casing adapted for actuating the conveyer in advance of slicing butter.
11. In a butter dispensing cabinet, a partition, means adapted for feeding a bar of butter through said partition, means at one side of said partition adapted for slicing butter and intermittently actuating said butter feeding means, and refrigeratory means at the opposite side of said partition.
- In testimony whereof I affix my signature in the presence of two witnesses.
